CORSET

Joseph J. Kispert, Hamden, Conn., assignor to
 I. Newman & Sons, Inc., New Haven, Conn., a
 corporation of Connecticut

Application September 28, 1935, Serial No. 42,681

7 Claims. (Cl. 2-36)

This invention relates to corsets and has for an object to provide an improved construction wherein a front lace structure is preserved having a yielding vest and a corset body formed at 5 the rear with a vertically stretchable panel and reinforcing members thereon.

Another object of the invention is to provide a corset provided with a corset body formed principally of inelastic material with the exception of 10 the rear panel which is formed principally of elastic material stretchable longitudinally of the corset and provided with one or more stiffening stays which function without restricting the stretching action of the panel.

15 A further object more specifically is to provide in a corset, a rear elastic panel extending from the lower edge to near the upper edge of the corset, the elastic panel being stretchable longitudinally of the corset and substantially non-stretchable circumferentially, with associated pockets 20 and stays therein formed so that part of the pockets will slide when the panel is being stretched and the remaining part will stretch.

In the accompanying drawing—

25 Figure 1 is an elevation of a corset embodying the invention, the same being spread out and viewed from the interior;

Figure 2 is a fragmentary sectional view through Figure 1 on the line 2—2, the same being 30 on an enlarged scale;

Figure 3 is an enlarged fragmentary transverse section view through Fig. 1 on the line 3—3;

Figure 4 is a view similar to Figure 2, but showing a slightly modified structure;

35 Figure 5 is a view similar to Figure 4, but showing a further modified structure;

Figure 6 is a fragmentary elevation showing a part of the corset illustrated in Figure 1, with a modified form of stay-pocket associated therewith;

40 Figure 7 is a view similar to the central part of the structure shown in Figure 1, but showing a modified form of elastic back panel.

Referring to the accompanying drawing by 45 numerals, 1 indicates the body of the corset, which is provided with what may be termed a back panel structure 2, side panels 3 and 4, and front panels 5 and 6. A vest structure is connected with the side panels 3 and 4, said vest structure comprising elastic sections 7 and 8 which are of a well-known structure.

Associated with the upper part of the corset body is a brassière 9. If desired, the brassière 9 could be eliminated without departing from the 50 spirit of the invention. Likewise, the sections 7

and 8 could be eliminated, although these are desired in a corset of this kind as they hold the corset in place while the lacing is applied.

It will be understood that this is a front lace 5 corset of the usual type except for the back panel 2. As illustrated particularly in Figure 1, the back panel 2 comprises an inelastic section 10 at the top and an elastic panel or section 11 at the bottom part. The section 11 extends from the lower edge of the garment upwardly any desired 10 distance, as, for instance, two-thirds of the length of the garment. The panel or section 11 is formed of elastic material which stretches and is elastic only longitudinally of the garment. This panel is substantially inelastic transversely or circumferentially. This back panel or section, when in use, permits a desired stretching of the garment when a person wearing the garment bends her body forwardly and then moves upright. In this way, the corset yields by reason of the section 11 15 instead of sliding on the body of the person.

The elastic action of section 11 is desirable, but it is also desirable to stiffen this part of the garment and in order to accomplish this result without affecting the stretchable or elasticity of 20 section 11, special stay pockets 12 and 13 have been provided. In each of these pockets there is provided a stay 14 which may be of steel or other material and of a length to extend substantially the full length of the respective pockets. 25 These pockets and the lower edge of section 11 are stitched to the lower edge of the garment preferably by the usual seams 15, but are otherwise unattached as far as the panel 11 is concerned. These pockets have at their upper ends 30 elastic extensions 16 and 17 which are connected to the pockets by suitable stitching and also by suitable stitching to the panel 10. At no point are the pockets or extensions 16 and 17 attached to the panel 11, but they lie against the panel and 35 thereby produce a reinforcing and stiffening action though not in any way interfering with the stretching of the panel. It will be observed that the elastic extensions 16 and 17 stretch longitudinally of the garment and naturally stretch at 40 the same time as the section 11. The two pockets and their stays are shown in Figure 1 and ordinarily this is sufficient. However, under some circumstances more or even less reinforcing members may be used. For instance, in Figure 6, a 45 fragmentary part of the rear panel of Figure 1 is disclosed wherein is present a stiffening structure 18 of a modified form. In this form of invention, there is provided a plurality of pockets 50 55 19 with a single sheet of fabric at the rear of

these pockets. An elastic extension 20 is provided at the upper end of member 18. As illustrated, there are two of these reinforcing members for the panel 11'.

5 Under some circumstances, the panel at the rear might be stretchable both longitudinally and circumferentially. In Figure 7, a rear section panel structure 11" is provided which is the same as that shown in Figure 1 except that the 10 section is elastic and stretchable circumferentially of the garment and also longitudinally of the garment. The stiffening members 12' and 13' may be identical with that shown in Figure 1 or if desired the pockets could be made from 15 elastic material similar to the material of section 11". In connection with the panel 2, it will be observed in Figure 1 that there may be provided a member 21 extending across the opening at the inverted V structure 22 so as to give 20 a desired tension to the upper part of the corset in connection with the brassière 9. It will be noted that the brassière 9 really merges into the rear of the corset or rather into the rear side sections 23 and 24 while the remaining part 25 of the corset is more or less independent whereby it may be swung around the body and secured in place after which the brassière part may be correctly positioned. The edges may be connected together in any suitable way, as, for instance, by hooks and eyes. It will also be noted that the entire part of the corset and brassière 30 may be formed of inelastic material while the lower part is provided with not only elastic sections 7 and 8, but the elastic gores 7' and 8', 35 said gores being elastic and stretchable circumferentially of the garment. The lower edge of the garment is provided with a binding member 25 of textile fabric which is more or less inelastic and very flexible and which is connected with 40 the section 11 by suitable line of stitching so that reinforcing members 12 and 13 may be connected by the same line of stitching to the binding 25 and thus may be mounted in place without being necessarily connected to the section 11 except 45 through the binding 25 and seam 15. By this arrangement, section 11 is permitted free movement independent of other parts and is reinforced by stay or reinforcing structures 12 and 13.

In Figure 4, there is presented a sectional view 50 similar to Figure 3, but showing a modified form of the invention wherein not only is there presented an elastic member 16, but also an elastic member 16' at the opposite end so that the stiffening stays are arranged centrally between these 55 two elastic members or extensions. In Figure 5, a further modified form is shown wherein the casing or pocket 26 is formed of the same kind of material as the section 11 and consequently is elastic and stretchable longitudinally of the 60 garment for its full length. Preferably, the stay 16' is also the full length of the pocket 26. By providing material 26 stretchable and elastic longitudinally of the garment it is not necessary to use elastic extensions at either end of the 65 pocket as the entire pocket is elastic.

Though the various pockets and stays as shown in the drawing are mounted adjacent an elastic section, it will be evident the same construction or inventive idea may be used on corsets which 70 have no elastic. For instance, on any of the conventional corsets now on the market various stays may be added and connected at the top and bottom respectively so that the stays will extend over those portions desired to be stiffened. While 75 the invention is desirable for front lace corsets

it may be used with step-in foundation garments or corsets of any kind without departing from the spirit of the invention.

I claim:

1. A corset provided with a back panel having 5 an inelastic upper portion, an elastic lower portion extending from the lower edge of the inelastic upper portion to the bottom of the garment and stiffening members connected respectively to the lower edge of the garment and to said upper portion and lying loosely against the elastic lower portion, each of said stiffening members being provided with an elastic section stretchable longitudinally of the corset whereby said elastic lower portion may stretch. 10

2. A corset including a body, a rear panel having an elastic section and stiffening structures lying loosely against the elastic section, each of said stiffening structures including a pocket secured at one end to the bottom of the garment, 20 a stay within the pocket and an elastic extension secured to the upper end of the pocket, said extension having one end secured to the rear panel above the elastic section, said stiffening structures being unattached except at their ends. 25

3. A corset comprising a body formed with a back having an inelastic top panel and elastic bottom panel, elastic longitudinally of the garment and a plurality of stiffening structures extending longitudinally of the garment and lying 30 against said elastic panel without being connected thereto intermediate the ends thereof, said stiffening structures being connected at one end to said inelastic section and at the other end to the lower edge portion of said body, each of 35 said stiffening structures having an elastic section elastic and stretchable longitudinally of the corset.

4. A corset having at the rear a panel provided with inelastic upper section and elastic lower 40 section, said lower section being formed of material elastic and stretchable in one direction and non-stretchable in a direction at right angle to its direction of stretchability with the material positioned to stretch longitudinally of the garment, and a pair of stiffening structures extending longitudinally over the rear panel, said stiffening structures being connected only at their respective ends respectively to the bottom edge of the elastic lower section and to the bottom 50 edge of said upper inelastic section, each of said stiffening structures having a part which is elastic and stretchable longitudinally of the garment. 55

5. A corset including a body, a rear panel and 55 stiffening structures lying against said rear panel but not connected therewith except at their ends, each of said stiffening structures including an inelastic pocket secured at one end to the bottom of said body, a flexible stay within the pocket 60 and an elastic forming an extension to said pocket positioned at the opposite end of the pocket and means connecting the upper end of said extension with the body near the top thereof. 65

6. A corset having at the rear a panel provided with an inelastic upper section and an elastic lower section, said lower section being formed of material elastic and stretchable in one direction and nonstretchable in a direction at 70 right angle to the direction of the stretchability with the material positioned to stretch longitudinally of the garment and a plurality of stiffening structures extending longitudinally over said lower section, said stiffening structures being ar- 75

ranged interiorly of the corset, and secured only at their respective ends to the lower edges respectively of said upper section and said lower section, each of said stiffening structures having an elastic part stretchable longitudinally of the corset whereby said lower section is reinforced and is allowed to stretch longitudinally of the corset.

7. A corset of the front lace type having a rear panel formed with an inelastic upper section and a lower elastic section, said elastic section being stretchable longitudinally of the garment and substantially non-stretchable circum-

ferentially thereof, a stiffening structure extending across said elastic section from the top to the bottom thereof, said stiffening structure having a pocket unconnected with said elastic section and a stay in said pocket extending substantially the full length of the pocket, and an elastic member secured at one end to the top of said pocket and at the other end to the lower edge of said inelastic section, said elastic member being stretchable longitudinally of the garment. 5 10
